No. 782,007.

PATENTED FEB. 7, 1905.

L. T. CRABTREE.

THIRD RAIL.

APPLICATION FILED APR. 14, 1904.

UNITED STATES PATENT OFFICE.

LEONARD TRACY CRABTREE, OF CRANDON, WISCONSIN.

THIRD RAIL.

SPECIFICATION forming part of Letters Patent No. 782,007, dated February 7, 1905.

Application filed April 14, 1904. Serial No. 203,116.

To all whom it may concern:

Be it known that I, LEONARD TRACY CRABTREE, a citizen of the United States, and a resident of Crandon, in the county of Forest and State of Wisconsin, have invented a new and Improved Third Rail, of which the following is a full, clear, and exact description.

My invention relates to third rails, my more particular object being to produce a third rail which is made in sections which are energized independently of each other, the only portion of the rail energized at a time being that immediately under the car.

Reference is to be had to the accompanying drawings, forming a part of this specification, in which similar characters of reference indicate corresponding parts in all the figures.

Figure 1 is a sectional side elevation of a portion of a railway embodying my improved third rail. Fig. 2 is a vertical cross-section upon the line 3 3 of Fig. 2 looking in the direction of the arrow. Fig. 3 is a section upon the line 4 4 of Fig. 2 looking in the direction of the arrow. Fig. 4 is a section upon the line 5 5 of Fig. 3 looking in the direction of the arrow. Fig. 5 is a vertical section upon the line 6 6 of Fig. 8 looking in the direction of the arrow. Fig. 6 is a section upon the line 7 7 of Fig. 6 looking in the direction of the arrow, the contact-lever being removed. Fig. 7 is a somewhat similar section showing a contact-lever in position and the magnet 25 suspended thereover; and Fig. 8 is a somewhat similar cross-section, but showing a protecting metallic trough in which the third rail and its accompanying parts are mounted.

The car-body is shown at 9 and is mounted upon wheels 10, engaging service-rails 11, these service-rails resting upon cross-ties 12 in the usual manner. A rail-support 13 rests directly upon the cross-ties 12, as indicated in Fig. 3. If desired, however, this rail-support may be partially inclosed within a trough-like metallic member 14, which in turn rests upon the cross-ties and may be provided with a flange 15, as indicated in Fig. 8.

Removably embedded within the rail-support 13 is a plate 16, of insulating material, and

below this plate 16 is a plate 17, likewise of insulating material. Between these two plates 50 and supported thereby is the live wire 18, which supplies energy to the system.

Disposed along the track are pockets 19 in the rail-support 13, and mounted within these pockets are contact-levers 20, each pivoted 55 directly upon the wire 18 and free to rock relatively thereto. Each contact-lever 20 is provided with an armature 21 and with a contact-point 22, which engages the rail-section 23 whenever the armature 21 rises. The several rail-sections 23 are normally dead, but become energized successively, owing to the engagement therewith of the contact-points 22. A plate 24, of insulating material, is placed directly over each contact-lever 20, as indicated 60 in Figs. 7, 8, and 9.

A number of magnets 25 26, preferably of the horseshoe form, but which may have any other desired form, are carried by the car 9. For convenience these magnets are mounted 70 upon a yoke 27 and depend from the same. This yoke carries a block 28 of insulating material, upon which is mounted the contact-brush 29. Another block, 28^a, of insulating material and provided with a contact-brush 75 29^a, is mounted upon this yoke 27. Wires 45 46 are used for energizing these several magnets, which are preferably connected in series.

The car-body 9 is supplied with legs 30 31 depending therefrom, the legs having vertical 80 slots 32 disposed adjacent to their lower ends, as indicated more particularly in Fig. 4. Plungers 33 34 are movably mounted within the lower ends of the legs 30 31, which are accordingly made hollow to receive the plungers, 85 as indicated in Fig. 4. Coil-springs 35 36 engage the plungers 33 34. The plunger 34 is provided with a pin 44 passing directly through the slot 32, this pin having a vertical play not exceeding the vertical measurement 90 of the slot 32. Bearing-brackets 37 38 are integrally connected with the plungers 33 34, these bearing-brackets being free to move slightly with relation to the legs 30 31. A shaft 40 is revolvably mounted within the bearing-brackets 37 38, this shaft being normally 95

pressed toward the left, as seen in Fig. 4, by means of a spiral spring 39, provided for the purpose. The trolley-wheel is shown at 42 and is engaged by the contact-brush 29, from which the current is supplied through the wire 41 to the motor mechanism of the car in the usual manner. The insulating-block 28 carries the wire 47, which is connected with the brush 29^a. The brushes 29 and 29^a are connected together by a wire 30^a. By means of the wires 45 and 46 the magnets may be energized by any suitable source of electricity, such as a storage-battery carried by a car, or may be shunted directly from the main circuit, as desired.

The operation of my device is as follows: The magnets 25 26 being energized and the car 9 being in motion, as soon as any one of the magnets approaches one of the contact-levers 20 the latter rises into the position indicated in Fig. 8. As there is a magnetic field around the poles of each magnet, the contact-levers 20 will rise even if the magnet be not directed over the same, the armature 21 rising in the proximate direction of the magnet or magnets immediately over the contact-lever. The magnets are sufficiently near each other, as indicated in Fig. 2, to maintain the contact-lever in its uppermost position, as shown in Fig. 8, until the entire series of magnets has passed over it. The several rail-sections 23 are normally dead; but each time the car passes one of these rail-sections the magnets cause one or more of the contact-levers 20 to rise, and thereby energize the rail-section. Should it happen that the magnets cover parts of two adjacent rail-sections, both sections are energized. The series of magnets is of such length that at least one of the armatures 21 is always energized, so that at least one of the contact-levers 20 presses its contact member 22 against a rail-section 23. Electric energy is therefore supplied continuously to the car as the same moves along from one rail-section to the other.

By the means above described the track from one of its ends to the other is comparatively safe to life and property, the current being supplied only where it is needed. A person

stepping upon a rail-section 23 at a point elsewhere than under the car is in no danger.

I do not limit myself to the particular form of mechanism above described, for the reason that various modifications of the same will readily suggest themselves to persons skilled in the art and various departures may be made without departing from the spirit of my invention.

Having thus described my invention, I claim as new and desire to secure by Letters Patent—

1. In a third rail, the combination of a rail-support of insulating material provided with pockets, a continuous feed-wire extending through said rail-support in the general direction of its length, plates of insulating material mounted within said rail-support and disposed respectively above and below said feed-wire so as to support the same, contact-levers mounted upon said wire and movable relatively thereto, said contact-levers being provided with armatures and with contact-points, conducting members to be engaged by said contact-points, trolley mechanism for engaging said contact members, and magnetic mechanism for attracting said armatures. 75

2. The combination of a continuous member of insulating material provided with pockets and with a continuous channel, a pair of plates mounted within said channel, one of said plates being superposed upon the other, a continuous conductor extending through said channel and disposed between said plates so as to be supported thereby, contact-levers disposed within said pockets and mounted upon said continuous conductor so as to be free to 85 rock, said contact-levers being provided with armatures and with contact-points, magnetic mechanism for attracting said armatures, and contact members to be engaged by said contact-levers. 90

In testimony whereof I have signed my name to this specification in the presence of two subscribing witnesses.

LEONARD TRACY CRABTREE.
